UNITED STATES PATENT OFFICE.

LUDWIG ANDREAS ZIEGLER, OF NEUSTADT-ON-THE-HAARDT, GERMANY.

DECALCOMANIA.

SPECIFICATION forming part of Letters Patent No 781,800, dated February 7, 1905.

Application filed December 29, 1903. Serial No. 186,940.

To all whom it may concern:

Be it known that I, LUDWIG ANDREAS ZIEGLER, a subject of the German Emperor, residing at Neustadt-on-the-Haardt, Germany, have invented certain new and useful Improvements in Decalcomania, of which the following is a specification.

In the practice of decalcomania or the process of transferring pictures from paper and other substances to glass, stoneware, and the like, a process which in the arts is frequently employed for the underglaze decoration of pottery, it is well understood that much difficulty is experienced by reason of the breaking off of portions of the transferred picture, particularly of the more delicate portions, such as streamers and the like. This difficulty is but partially obviated by the use of varnish in the process of transferring and there are obvious disadvantages in the employment of varnish as compared with water.

It is therefore the object of this invention to prevent as far as possible the breaking of the pictures during the process of transferring and to accomplish this result without the use of varnish, although the improvement is applicable to the process when carried out with varnish as well as with water.

To accomplish the desired result, a tanning material of any suitable character—such, for example, as extract of quebracho—is applied to the picture. Such material not only makes the transferred picture less liable to breakage during the process of transfer, but it facilitates the separation of the picture from the paper or other substance upon which it is printed and assists in effecting a close union or adhesion of the picture to the stoneware, pottery, or other article to be ornamented.

The invention is illustrated in a general way in the accompanying drawings, in which—

Figure 1 represents on a somewhat enlarged scale a section through an article which has been ornamented in accordance with the invention; and Fig. 2 is a similar representation showing a modification.

It will be obvious that the tanning material can be applied to the picture in many different ways. One convenient way is to make a

solution of the tanning material, preferably an aqueous solution, which solution is applied to coat the base *a*, which may be of paper or of a fabric, such as linen or cotton cloth and the like, and to saturate the picture *b*, the picture then being transferred upon the article to be ornamented *c* by pressure, the tanning material being indicated in the drawings by the reference-letter *c*. If it is preferred to use the tanning material in a dry state, it may be dusted as a powder upon the picture while the latter is moist, the picture, as in the first case, being afterward applied to the article to be ornamented *c* and caused to adhere thereto by pressure. The powder, if desired, may be dusted upon the picture immediately after it has been printed and while it is still moist from the press. For very fine designs and for such designs as have streamers or small projections running out from the body thereof it will be found preferable to coat the finished picture with varnish and to dust upon this varnish coat the tanning-powder. In this way the tearing or breaking of the picture is more easily prevented, as the whole picture is strengthened and both the fine parts and the projecting parts thereof are more firmly united together and to the body portion of the picture. (See Fig. 2, where the varnish-coat is indicated by the reference-letter *d*.) Again, the tanning material may be mixed with the varnish-coat instead of being added afterward, or it may be added to the colors which form the picture. In such cases the tanning material is first preferably dissolved in turpentine or mixed with oil of lavender and then rubbed up with or dissolved in the color or the varnish, as the case may be. Furthermore, the invention may be carried out by saturating the paper upon which the pictures are printed with the tanning material, or such paper may be impregnated with the tanning material in the manufacture thereof.

It is unnecessary to enumerate herein all of the substances which may be employed as tanning material in carrying out the invention. Besides extract of quebracho tannic acid may be employed and such substances as the chromates and the alums as well as other sub-

stances. The term "tanning material" accordingly will be understood to include such substances.

I claim as my invention—

5 The improvements in decalcomania or the process of transferring pictures from paper or other material to a base, which consists in applying a tanning material without the ad-

mixture of any adhesive substance between the picture and the base as a cement.

This specification signed and witnessed this 14th day of December, A. D. 1903.

LUDWIG ANDREAS ZIEGLER.

In presence of—

JOHANN CARL KEIPPER,
MICHAEL ZIMMERMAN.
